INVENTOR

Frederick Schmidgall,
By C. W. Miles,
Attorney,

UNITED STATES PATENT OFFICE.

FREDERICK SCHMIDGALL, OF CINCINNATI, OHIO.

DOOR LATCH AND LOCKING APPARATUS.

1,334,320.

Specification of Letters Patent. Patented Mar. 23, 1920.

Application filed March 31, 1919. Serial No. 286,289.

To all whom it may concern:

Be it known that I, FREDERICK SCHMIDGALL, a citizen of the United States, residing at Cincinnati, in the county of Hamilton and State of Ohio, have invented certain new and useful Improvements in Door Latch and Locking Apparatus, of which the following is a specification.

My invention relates to improved latch and locking mechanism for the doors of cold-storage rooms and similar purposes. One of its objects is to provide mechanism adapted to be unlatched and opened from the interior of the room by direct pressure 15 on a member carried upon the interior face of the door, as for instance by the striking or bumping of a truck against said member. Another object is to provide improved latch and locking mechanism. Another object is to 20 provide means to hold the door in closed position against its tendency to rebound when sharply closed, and also to provide adjustable means for that purpose. Another object is to provide spring tensioned latch and 25 locking means and means to adjustably increase or decrease such tension. My invention also comprises certain details of form, combination, and arrangement, all of which will be fully set forth in the description of 30 the accompanying drawings, in which:

Figure 1 is an outside elevation of a cold-storage room door and door-frame ready to be placed in the wall of a cold-storage room, with my improved latch mechanism applied 35 thereto.

Fig. 2 is a plan view of the same, with the latch mechanism in the closed position.

Fig. 3 is a view similar to Fig. 2 with the latch mechanism in its unlatched position.

Fig. 4 is a sectional view on line 4-4 of Fig. 2.

Fig. 5 is a sectional detail on line 5-5 of Fig. 2.

The accompanying drawings illustrate 45 the preferred embodiment of my invention, in which 6 represents a door and 7 a door-frame connected together by hinges 8. At the opposite side of the door frame from the hinges is a latch keeper 9 having an eye 10 50 therein.

The latch and locking mechanism carried on the door comprises frame members 11 and 12 rigidly attached to the door. The frame member 11 has a horizontally projecting ledge 14 on which a latch member 15 rests, and above which latch member is an-

other horizontally projecting ledge 16. A pin 17 projects through perforations in the ledges 14 and 16 and through a curved slot 18 in the latch member 15 to hold the latch member in position in the channel between the ledges 14 and 16 with a limited movement relative to said ledges and the frame member 11. At the rear end of the ledge 14, and an integral part of frame 11 is a spring 65 housing 19 having a vertical cylindrical or tubular recess to receive and house a coiled spring 20. One end 21 of the spring 20 is engaged by an adjusting nut or collar 22 which is provided with a series of ratchet teeth 23 set in one direction to engage corresponding ratchet teeth set in the opposite direction and carried by the spring housing 19. A portion 24 of the collar 22 projects below the spring housing 19 and is adapted 70 to be engaged by a pin or spanner wrench to adjust the collar 22 so as to secure any desired tension of the spring 20 upon the latch. The opposite end 25 of the spring 20 engages a hand lever 26 which is employed to release the latch and open the door from the outside, and said spring tension tends to hold the free end of said hand lever normally pressed against the face of the frame member 11. The hand lever 26 80 has a square or rectangular eye 27 to receive endwise a squared or rectangular shaft 28 about the lower end of which the spring 20 is coiled. By reason of the engagement of said shaft in the rectangular eye 27 of the 90 hand lever the said shaft and hand lever move in unison about the axis of said shaft.

The upper end of the shaft 28 seats in a rectangular socket in the member 29 which is journaled exteriorly in the frame member 95 12, so that the member 29 also turns with the shaft 28 about the axis of said shaft. The member 29 has a transverse slot 30 in which is seated an adjustable crank arm 31, which has ratchet teeth on its under face 100 to lock the crank arm to said slot 30, and a set screw 32 serves to force said ratchet teeth into engagement with the bottom face of the slot 30. The crank pin 33 of the crank arm 31 slips over the end of and 105 engages in rear of a keeper 34 rigidly attached to the door frame to prevent the door from rebounding from the door frame when the door is swung to closed position. The crank arm 31 may be adjusted from 110 time to time into close engagement with the keeper 34, to take up and avoid lost motion.

At its forward or free end the hand lever 26 is provided with a downwardly directed pin 35 which engages in rear of a finger 36 carried by the latch member 15, which pin 5 35, as the hand lever is drawn or forced away from the frame member 11 against the tension of the spring, engages the finger 36 so as to draw the latch member outwardly and rearwardly, by reason of the pin 17 10 traveling from one end of the slot 18 to the other, and thereby disengages the keeper 9 from the forked forward end 37 of the latch member 15. At the same time the tooth 38 of the latch member 15 is thrown 15 to a position where it enters a recess 39 in the frame member 11 and thereby locks the hand lever 26 and latch member in substantially the position illustrated in Fig. 3 20 relative to the frame 11 and door 6 so long as the door is in the open position. As the door is returned to a closed position the nose 40 of the latch member 15 first comes in contact with the keeper 9 and tilts the latch member on the pin 17, thereby 25 releasing the tooth 38 from the recess 39, whereupon the latch member 15 and hand lever 26 assume substantially the position illustrated in Fig. 2. At the same time the shaft 28 and crank pin 33 moving with the 30 hand lever and energized by the spring 20, engage the keeper 34 to firmly lock the door to the door-frame.

In order that the door may be conveniently opened from the interior of the cold 35 storage room I provide a bar 42 having one end turned at right angles and engaged in a perforation through the hand lever 26 so that the main section of the bar 42 is movable endwise through a perforation 40 through the door 6 and a frame member 44 rigidly attached to the inner face of the door. A yoke-shaped or loop-shaped actuating member 45 is pivotally held in position relative to the door by means of frame member 44. A tongue 46 carried by the member 45 bears against the face of the door to hold the member 45 a short distance away from the face of the door and to limit the pivotal movement of said member 45. The end of 50 bar 42 engages one arm of member 45 and holds it away from the inner face of the door when the door is in closed position as illustrated in Figs. 2 and 4. In order to open the door from the interior the member 45 is forced from the full line position Fig. 4 to the dotted line position, which shifts the bar 42 endwise and actuates the hand lever 26 and the latch member 15 and pin 33 to release and open the door. The 55 loop-shaped member 45 and frame member 44 and bar 42 may be employed without change on doors opening right hand or left hand, as the bar 42 may be set to engage either one of the side bars of the loop 45. The member 45 is also in position to be

conveniently actuated both by hand, and by bumping a floor supported hand truck against it, to cause the door 6 to be opened from the interior. After the truck has passed through the door, all that is required 70 to close the door is for the operator of the truck to swing or push the door with sufficient force to close it, whereupon it will automatically latch and lock itself tightly in closed position so as to insure a minimum escape of cold air from the storage room. Adjustment of the member 33 and the tension of the spring 20 may be quickly made at any time to keep the door in perfect operating condition. Shaft 28 may 75 extend to the opposite end of door 6 and having locking members 33 and 34 at each end.

The apparatus herein illustrated and described is capable of considerable modification without departing from the principle 85 of my invention.

What I claim is.

1. A latch mechanism for doors comprising a door, a door frame, a keeper rigidly 90 attached to the door frame, a latch frame rigidly attached to the door, a latch member carried by said latch frame having a forked end to receive and engage the keeper, a tooth to engage and lock the latch 95 relative to the latch frame, said latch member having an endwise movement and a rocking movement relative to the latch frame, and a spring actuated hand lever having engagement with said latch member 100 to move and disengage the latch member from its keeper and to lock the latch member and hand lever relative to the latch frame until released by contact of the latch member with the keeper.

2. A latch mechanism for doors comprising a door, a door frame, a keeper rigidly attached to the door frame, a latch frame rigidly attached to the door, a latch member carried by said latch frame having a 110 forked end to receive and engage the keeper, a tooth to engage and lock the latch relative to the latch frame, said latch member having an endwise movement and a rocking movement relative to the latch frame, a hand lever having engagement with said latch member to move and disengage the latch member from its keeper and to lock the latch member and hand lever relative to the latch frame until released by contact of the latch 115 member with the keeper, a spring to energize said hand lever, and means to adjustably tension said spring.

3. A latch mechanism for doors comprising a door, a door frame, a keeper rigidly 125 attached to the door frame, a latch frame rigidly attached to the door, a latch member carried by said latch frame having a forked end to receive and engage the keeper, a tooth to engage and lock the latch rela- 130

5 tive to the latch frame, said latch member having an endwise movement and a rocking movement relative to the latch frame, a hand lever carried pivotally relative to said latch frame and having engagement with said latch member to move and disengage the latch member from said keeper and to lock the latch member and hand lever relative to the latch frame until released by contact of 10 the latch member with said keeper, a spring to energize said hand lever, a shaft movable with said hand lever and journaled near the edge of said door, a locking keeper carried rigidly by said door frame at the end of 15 said shaft, and a crank pin carried by said shaft to engage said locking keeper to positively lock the door in closed position.

20 4. A latch mechanism for doors comprising a door, a door frame, a keeper rigidly attached to the door frame, a latch frame, rigidly attached to the door, a latch member carried by said latch frame having a forked end to receive and engage the keeper, a tooth to engage and lock the latch relative to the 25 latch frame, said latch member having an endwise movement and a rocking movement relative to the latch frame, a hand lever having engagement with said latch member to move and disengage the latch member from its keeper and to lock the latch member and hand lever relative to the latch frame until released by contact of the latch member with 30 said keeper, means carried on the inner face of the door operable to move said hand lever to unlatch the door from within, and a spring to energize said hand lever.

35 5. A latch mechanism for doors comprising a door, a door frame, a keeper rigidly attached to the door frame, a latch frame rigidly attached to the door, a latch member carried by said latch frame having a forked end to receive and engage the keeper,

40 a tooth to engage and lock the latch relative to the latch frame, said latch member having an endwise movement and a rocking movement relative to the latch frame, a hand lever having engagement with said latch member to move and disengage the latch member from its keeper and to lock the latch member and hand lever relative to the latch frame until released by contact of the latch member with said keeper, a yoke-shaped latch releasing member carried 45 adjustably on the inner face of the door and operably connected through the door with 50 said hand lever to unlatch the door from within, and a spring to energize said hand lever.

55 6. A latch mechanism for doors comprising a door, a door frame, a keeper rigidly attached to the door frame, a latch frame, rigidly attached to the door, a latch member carried by said latch frame having a forked end to receive and engage the keeper, a tooth to engage and lock the latch relative to the latch frame, said latch member having an endwise movement and a rocking movement relative to the latch frame, a hand lever having engagement with said latch member to move and disengage the latch member from its keeper and to lock the latch member and hand lever relative to the latch frame until released by contact of the latch member with said keeper, means carried on the inner face of the door and 60 adapted to be connected either right hand or left hand operably with said hand lever through the door to move said hand lever to unlatch the door from within, and a spring to energize said hand lever.

65 75 80 In testimony whereof I have affixed my signature.

FREDERICK SCHMIDGALL.
